SEAM FOR STITCHED ARTICLES

Darwin G. Smith, Bridgeport, Conn., assignor to
The Singer Manufacturing Company, Elizabeth, N. J., a corporation of New Jersey

Application November 14, 1947, Serial No. 786,013

6 Claims. (Cl. 112—269)

1

This invention relates to seams for stitched articles, and more particularly to an improved overedge seam which is adapted for use in the production of eyelets and buttonholes.

The primary object of the present invention is to provide an overedge seam which is superior in both quality and durability.

Another object of the invention is to provide an improved overedge seam having the characteristic of presenting an embossed or padded effect on one face of the body material in which the seam is formed and particularly desirable in connection with eyelets and buttonholes.

A further object of the present invention is to provide a machine-made eyelet or buttonhole having an appearance closely approximating a hand stitched eyelet or buttonhole.

The above and other more specific objects will appear upon reading the following specification and claims and upon considering in connection therewith the attached drawings to which they relate.

Referring now to the drawings:

Fig. 1 is a plan view of one face of a body material provided with an eyelet made in accordance with the present invention.

Fig. 2 is a plan view of the other face of the body material and eyelet shown in Fig. 1.

Fig. 3 is an enlarged development of the stitching forming the eyelet.

Fig. 4 represents a sectional view taken substantially along the line 4—4, Fig. 2.

Referring more in detail to the drawings, the eyelet is shown as formed in a piece of body material or work W from which has been cut a center eye 10. The stitching is formed by the concatenation of a depth-stitch thread 11 and an edge-embracing or overedge thread 12. The depth-strokes of the thread 11 penetrate the material W back from the edge thereof and extend circumferentially of the eyelet, while the overedge thread 12 embraces the edge of the material in the form of thread loops extending radially of the eyelet and anchored in place by the depth-stitch thread 11.

The eyelet shown in the drawings can be produced by a sewing machine made in accordance with that forming the subject of the pending patent application Serial No. 786,017 filed on Nov. 14, 1947 now Patent No. 2,515,740, dated July 18, 1950 by Darwin G. Smith and Harold C. Faulkner. As illustrated and described in that patent application, the stitch-forming mechanism includes a depth-stitch thread-handling upper straight needle N, an overedge thread-

2

handling lower curved needle C and a looper L. In operation, the straight needle N penetrates the material back from the edge thereof and presents a thread-loop to the looper L which, after seizing the thread-loop, expands it for entrance by the lower curved needle C. After entering the expanded thread-loop, the curved needle C carries its thread 12 about the edge of the material to the opposite face thereof and presents a loop of overedge thread for entrance by the straight needle N on its next downstroke.

It will be understood from Fig. 3 that in forming the improved seam, a loop 13 of the depth-stitch thread 11 is carried through the material 15 by the straight needle N and that the thread-loop 13 thus formed is then seized and expanded by the looper L. The looper, during its loop-expanding stroke, moves the thread-loop 13 in a direction beneath the limb 14 of overedge thread 20 extending from the last stitch to the eye in the curved needle C. The curved needle C then enters the expanded thread-loop 13, thus passing the thread-loop 15 of the overedge thread 12 through the expanded thread-loop 13. The thread-loop 15 is then carried about the edge of the material, which defines the cut eye 10, and across the upper face of the material to a position directly beneath the straight needle N so that the loop of overedge thread can be entered 25 and thereby enchain with the depth-stitch thread. As the depth-stitch thread-loop 13 is tightened by the usual sewing machine thread take-up devices, the said thread-loop is twisted, as indicated at 16 in Fig. 3, the twist in the finished eyelet preferably being drawn into and hidden in the body material between the opposite faces thereof.

It will be observed, particularly in Figs. 3 and 4, that on one face of the material there are long 40 loops 17 of overedge thread, which loops extend substantially radially from the edge of the material back to the point of penetration of the depth-stitch thread 11, while on the opposite face of the material the overedge thread is formed into 45 short loops 18 which also extend in a direction substantially radially back from the edge of the material. These short loops 18 are enchain with the loops 13 of depth-stitch thread, which loops 13 continue from the ends of loops 18 across 50 the face of the material to the point at which the depth-stitch thread penetrates the material W. As will be seen in Fig. 4, the overedge thread-loops 18 pass through the depth-stitch thread-loops 13 in a direction away from the adjacent face 19 of the body material, while on the op-

posite face 20 of the body material the depth-stitch thread-loops 13 pass through the overedge thread-loops 17 in a direction toward said face 20 of the body material. The enchaining of the thread-loops 18 and 13 between the edge of the material and the point of penetration of the depth-strokes, coupled with the fact that the overedge thread-loops 18 pass through the depth-stitch thread-loops 13 in a direction away from the face 19 of the body material, raises the thread-loops 18 and 13 relative to the material face 19, thereby producing in the completed eyelet a padded or embossed appearance on one face of the body material which simulates very closely the appearance of a hand sewn eyelet.

The concatenation of the edge-embracing thread 12 and the depth-stitch thread 11 is such that the stitches comprising the overseam can be readily set without requiring excessive tensioning of the two threads 11 and 12. Thus, the threads in the completed seam are not excessively strained and eyelets formed with the present seam are uniform in size and durable. In addition, the eyelet is neat in appearance owing to the absence of a drawn or puckered body material adjacent the eyelet. Moreover, the ease with which the stitches comprising the present seam can be set permit the production of round eyelets free of distortion in flimsy body material.

Having thus set forth the nature of the invention, what I claim herein is:

1. An overseam for an edge of a body material, comprising depth-stitch thread-loops penetrating the body material back from the edge thereof, and edge-embracing thread-loop concatenated with said depth-stitch thread-loops upon opposite faces of the body material, said edge-embracing thread-loops on one face of said material passing through said depth-stitch thread-loops in a direction away from said face of the body material, and said depth-stitch thread-loops on the other face of said body material passing through said edge-embracing thread-loops in a direction toward said other face of said body material.

2. An overseam for an edge of a body material, comprising depth-stitch thread-loops penetrating the body material back from the edge thereof, and edge-embracing thread-loops concatenated with said depth-stitch thread-loops upon opposite faces of the body material, said edge-embracing thread-loops on one face of said material passing through said depth-stitch thread-loops in a direction away from said face of the body material, and said depth-stitch thread-loops on the other face of said body material passing through said edge-embracing thread-loops in a direction toward said other face of said body material, said depth-stitch thread-loops being twisted between the points of concatenation with said edge-embracing thread-loops at the opposite faces of the body material.

3. An overseam for an edge of a body material, comprising depth-stitch thread-loops penetrating the body material back from the edge thereof, and edge-embracing thread-loops concatenated with said depth-stitch thread-loops upon opposite faces of the body material, said edge-embracing thread-loops on one face of said material passing through said depth-stitch thread-loops in a direction away from said face of the body material and at a point intermediate the edge of the body

material and the penetration of the body material by said depth-stitch thread-loops, and said depth-stitch thread-loops on the other face of said body material passing through said edge-embracing thread-loops in a direction toward said other face of said body material.

4. An overseam for an edge of a body material, comprising depth-stitch thread-loops penetrating the body material back from the edge thereof, and edge-embracing thread-loops concatenated with said depth-stitch thread-loops upon opposite faces of the body material, said edge-embracing thread-loops on one face of said material passing through said depth-stitch thread-loops in a direction away from said face of the body material and at a point intermediate the edge of the body material and the penetration of the body material by said depth-stitch thread-loops, and said depth-stitch thread-loops on the other face of said body material passing through said edge-embracing thread-loops in a direction toward said other face of said body material, said edge-embracing thread-loops on said other face of the body material extending from the edge of the body material back to the point of penetration of said depth-stitch thread-loops.

5. An overseam for a body material having an edge defining an opening, comprising depth-strokes progressively formed in the body material concentrically with and in spaced relation to said edge, said depth-strokes including body-material penetrating loops of thread secured by edge-embracing loops of thread passing through said opening and extending radially from said edge upon opposite faces of said body-material, said edge-embracing thread-loops on one face of said body material passing through said depth-stitch thread-loops in a direction away from said face of the body material, and said depth-stitch thread-loops on the other face of said body material passing through said edge-embracing thread-loops in a direction toward said other face of said body material.

6. An overseam for a body material having an edge defining a rounded opening, comprising depth-strokes progressively formed in the body material concentrically with and in spaced relation to said edge, said depth-strokes including loops of thread penetrating the body material and on at least one face thereof extending radially toward said edge, and edge-embracing loops of thread passing through said rounded opening and extending radially from said edge upon opposite faces of said body-material, said edge-embracing thread-loops on one face of said body material passing through said depth-stitch thread-loops in a direction away from said face of the body material, and said depth-stitch thread-loops on the other face of said body material passing through said edge-embracing thread-loops in a direction toward said other face of said body material.
